BUILDING ROOF FASCIA

Robert P. Orr, Overland Park, Kans., assignor to Butler Manufacturing Company, Kansas City, Mo., a corporation of Missouri

Filed July 3, 1967, Ser. No. 7,689

Term of patent 14 years

U.S. Cl. D13—1
Int. Cl. D25—01

Fig. 1.

Fig. 2.

Fig. 3.

Fig. 4.

Fig. 5.

FIG. 1 is a perspective view of a building roof fascia embodying my design as applied to a typical building structure, the building itself being shown in broken lines;

FIG. 2 is an enlarged front elevational view of a panel embodying my design;

FIG. 3 is a side elevational view of said panel, taken from the right hand side of FIG. 2;

FIG. 4 is an enlarged cross sectional view taken along line 4—4 of FIG. 2 in the direction of the arrows; and

FIG. 5 is an enlarged cross sectional view taken along the line 5—5 of FIG. 2 in the direction of the arrows.

The dotted line showing is for illustrative purposes only.

I claim:

The ornamental design for a building roof fascia, as shown and described.
